TWINE CUTTER

Filed June 4, 1929

Fig. 1.

UNITED STATES PATENT OFFICE

HERBERT W. FENTON, OF DOWAGIAC, MICHIGAN

TWINE CUTTER

Application filed June 4, 1929. Serial No. 368,230.

My invention relates to improvements in twine-cutters, and more particularly to that type associated with a ring adapted to be worn on a finger of either hand.

5 Twine cutters of this type are particularly adapted for use by clerks in stores, factories, warehouses, and many other places, such as on farms and gardens; in fact, for use by any person finding it necessary to cut twine,

10 string, thread, or any other cord material.

My improved twine cutter, although capable of use as above stated, is particularly designed and constructed for use in tying up grape vines, and other plants necessary 15 to train on suitable supports, as it is worn on the hand in such a manner that it will not interfere with the tying operation, but will be handy for cutting the twine or other cord material used for such purpose after 20 each tying operation.

My invention has for one of its objects the production of a twine cutter of novel and simple construction associated with a ring or ring support that it can be adjusted 25 to any desired angle with reference to the axis of said ring or support, or be positioned parallel therewith, and regardless of its position, be retained as adjusted.

Another object of my invention is the 30 provision of a double edge cutter, in a twine cutter, so that twine or other cord material can be cut by either of two opposite movements given the device, which is a very desirable feature of my invention, when cutting the twine after tying grape vines to 35 their supports, due to the fact that often-times surrounding parts interfere with the cutting action if the device is moved in a certain direction, whereas freedom of action and non-interference by surrounding 40 parts would be assured if the device were moved in the opposite direction.

A further object of my invention is the 45 production of a cutter element which is readily removable from its holder so that it can be re-sharpened when dull, or be replaced with another cutter element.

With the above and other objects to appear hereinafter, my invention consists in 50 the novel features of construction and in

the arrangement and combination of parts to be hereinafter described and more particularly pointed out in the subjoined claims.

In the drawings:

Fig. 1 is a perspective view of my improved twine cutter, showing the same as worn on a finger of the user. 55

Fig. 2 is a side elevation of the same.

Fig. 3 is a plan view.

Fig. 4 is an enlarged section, taken on line 60 4—4, Fig. 2.

Fig. 5 is a section, taken on line 5—5, Fig. 4, on a reduced scale.

Fig. 6 is a detachable perspective view 65 of the cutter element.

Reference being had to the drawings in detail, the numeral 7 designates a carrying member or object for the cutter proper, in the form of a finger ring which may be constructed of any suitable material and in different sizes; it being provided with a tapped opening 8 in its surrounding wall for the reception of a screw-threaded stud 9 extending inwardly from a blade-support or holder 10. This blade support, or cutter-element support as it may be termed, may be varied in shape, but preferably has two wings 11 extending from opposite sides of a plane passing axially through the screw-threaded stud 9. Said support is comparatively thin 70 and has opposite ends rounded inwardly, or toward the finger ring 7, as at 12, to prevent catching the twine or becoming entangled with other objects, while the inner edge thereof, or more particularly, the inner 75 edges of the two wings are notched or deeply concaved, as at 13, to expose comparatively large portions of the blade or cutter-element to be presently described.

The blade or cutter-element support 10 is 80 slotted, as at 14, from its outer edge inwardly toward the screw-threaded stud 9, so that substantially two side members 15, 16 are provided which are spaced apart a sufficient distance to receive a blade or cutter-element 85 17 between them.

The blade or cutter-element is substantially triangular in shape, as shown in Fig. 6; two edges 18 thereof being sharp and being exposed at the notched portions of the sup- 100

port 10. Attention is here invited to the fact that the support or holder 10 conforms somewhat to the outline of the blade or cutting-element, except for the notches 13 in said support and its projecting stud 9; and that the slot 14 in said support or holder terminates a short distance from the screw-threaded stud 9 in a wall 19 having a retainer lug 20 extending into said slot. The two sharpened or cutting edges 18 of the blade or cutting-element are disposed at obtuse angles to each other and separated by an edge portion 21 conforming to the shape of the inner wall 19 of the slot 14 in the support 10. It therefore has a notch 22 extending inwardly from the edge portion 21 which receives the retainer lug 20 extending into said slot and forming part of said wall.

Arranged in the side members 15 and 16 of the support or holder 10 are alined screw holes 23, 24, respectively, and formed in the blade or cutting-element is a screw hole 25 which registers with the screw holes 23 and 24. A securing screw 26 is passed through the screw-hole 23 in one side member, which is countersunk to receive the head of said screw, and through the screw hole 25 in the blade or cutter-element and it is screw threaded into the screw-hole 24 in the other side member, which screw-hole is tapped for the purpose.

When the blade or cutter-element is positioned within the support or holder 10, it is clamped between the side members 15 and 16, and in the event that the securing screw 26 becomes loosened the blade is held against movement by the retainer lug 20. Assurance is therefore had that regardless of the strain applied in the act of cutting twine or other cord-like material a rigid cutting edge will always be presented to the twine or like material and be maintained during the act of cutting.

It is to be noted that the screw-threaded stud is comparatively long and that on it, between the finger ring 7 and the inner edge of the support or holder 10, a jamb-nut 27 is threaded. This jamb-nut locks against the outer surface of the ring and prevents turning of the screw stud and consequently swiveling movement of the support or holder. When said jamb-nut is loosened from contact with the finger ring, the blade support or holder 10 may be turned into any position, either to the position shown in full lines in Fig. 3, at right angles thereto, or into any intermediate angular position, as shown for example by dotted lines in said figure. The tightening of the jamb-nut 27 against the finger ring will retain the support in the desired adjusted position.

It will be quite apparent that when the blade or cutter-element is in any particular position with reference to the finger ring it may be most convenient for one user and

exceedingly awkward for another. The position and angle of the twine 28 or other cord-like material to be cut may suggest a change of angle of the blade by the same user, and he may find it easier to cut with one exposed cutting edge than the other, depending on the direction of the strand of twine to be cut; this being clearly shown in Fig. 1.

The double cutting edge exposure, with one cutting edge at an angle to the other, is therefore a decided advantage in the use of this invention, and particularly the location of cutting edges at opposite sides of the center of the support, or more particularly stated with reference to the finger ring, at opposite sides of a radial plane.

This device may be used on any finger, and if desired, two or more finger rings may be furnished with each blade support; thus enabling different persons to use the same finger support with finger rings to fit the fingers of the different users.

It may also be stated, that for some kinds of work, it may be found of advantage to use the device on the palm-side of the hand; but whether used on the outer or inner side of the hand and regardless of the finger it is used on, the device is easy to operate by either a right or left hand user; its double cutting edge and its adjustability making it universal to meet all conditions.

Having thus described my invention, what I claim is:—

1. A twine cutter, comprising a blade-holder of substantially triangular shape and having its inner edge formed by two sides of the triangle and its outer edge by the third side, said holder being slotted from its outer edge inwardly through the end portion of said inner edge to form two spaced side members connected integrally at a point centrally between the two first mentioned sides of the triangle, said side members being provided with alined holes, a cutting blade positioned between said side members and having a hole registering with the holes in said side members, and fastening means entered in the holes of said side members and said cutting blade, said cutting blade having cutting edges exposed at the inner edge of said blade-holder.

2. In combination with a finger ring, a blade-holder having a supporting stud centrally between its ends entered in said ring for rotatably adjusting said holder on said ring, means for securing said stud against movement when said holder is adjusted to desired position, and a cutting blade carried by said blade-holder and having cutting edges exposed at opposite sides of said stud, said cutting edges being at an angle to each other and capable of being disposed parallel with a plane passing axially through the ring or at any angle thereto.

3. A twine cutter, comprising a blade-holder of substantially triangular shape and having two of its sides forming the inner edge of said holder and the remaining side the outer edge, said holder being slotted from its outer edge inwardly to form two spaced side members for said holder connected together at its inner edge centrally between the ends of said holder, said central connection forming the inner wall of the slot so formed and said inner wall having a retainer lug between its ends extending into said slot, said slot opening through portions of the two first-mentioned sides of the triangle and said side members having aligned screw holes near the outer edge of the holder, a cutting blade of substantially triangular formation held between said side members and having a screw hole registering with the screw holes in said side members and a notch at its inner edge into which said retainer lug fits, the cutting edges of said blade being exposed at the inner edge of said blade-holder at opposite sides of said notch and retainer lug, and a screw entered in said registering screw holes and clamping said blade between said side members.

In testimony whereof, I affix my signature.

30 HERBERT W. FENTON.
